UNITED STATES PATENT OFFICE

WILBUR R. POUNDER, OF CHICAGO, ILLINOIS, ASSIGNOR TO HUBBARD & CO., OF CHICAGO, ILLINOIS, A CORPORATION OF ILLINOIS

ANCHOR

Application filed November 20, 1931. Serial No. 576,320.

My invention relates to anchors, more particularly to anchors comprising a rod and a formed head containing integrally formed thimbles for the reception of strain members.

It is old in the prior art, of which I am aware, to provide anchors consisting of a rod containing a head in which is formed a thimble eye or a plurality of thimble eyes for the reception of strain members. These thimble eyes are themselves shaped as round bottom grooves extending through the head of the anchor in an arcuate path of long radius so that a strain member, such as a stranded guy wire, can be attached directly to the guy rod without the use of separate shield members or thimbles.

Such anchors are provided with rods several feet in length to permit the use of the anchor as a guy rod, and are also provided with rods that are but several inches in length to permit the use of the anchor for attaching a strain member to a pole top.

My present invention improves the anchors of the prior art by providing a head arranged to receive one, two or three strain members, the head being shaped so that the stresses placed upon the rods by a single strain member, or by two strain members, or by three strain members, are extended axially along the rod itself. My improved anchor head is self-braced against deformation under stresses placed upon it by a single strain member, or by two strain members, or by three strain members. My improved anchor is very rugged, and can be economically fabricated and cheaply installed.

My invention will be best understood by reference to the accompanying drawing in which a preferred embodiment of it is shown by way of example only and in which:—

Figure 1 is a perspective view of the anchor with a single strain member attached thereto;

Figure 2 is a perspective view of the anchor with two strain members attached thereto;

Figure 3 is a perspective view of the an-

chor with three strain members attached thereto;

Figure 4 is a plan view of the anchor; and

Figure 5 is a fragmentary cross sectional view of the anchor taken substantially along the line 5—5 of Figure 4 looking in the direction of the arrows. 55

As will be seen in Figures 4 and 5, my improved anchor comprises a strain rod 1 having an integrally formed head indicated 60 generally at 2. This head comprises a pair of arcuate arms 3 and 4 diverging from the end of the rod to form the wide portion of the head 2. At the outer end of these arms 3 and 4 are extensions 5 and 6 which converge toward a point located beyond the head 2 and on the axis of the anchor rod 4. These arm extensions 5 and 6 together form the narrow outer portion of the head structure. 65

At the junction of the arm portions 3 and 5 and 4 and 6, respectively, is a transverse bridge wall 7 formed integrally with the arm members, and shaped to define an opening 8 which is shaped substantially as a cardioid. 70 The arm extensions 5 and 6 are joined together by a thimble portion 9 which is shaped to form a substantially circular opening 10 located in the narrow outer part of the head 2. 75

As will be seen in Figure 5 the walls of the cardioid opening are of elliptical cross section and there are no sharp corners or projections that would tend to injure a strain member upon coming into contact with the same. The cross member or bridge wall 7 is likewise formed of generally elliptical cross section for the same reason, and the end wall 9 of the head is similarly formed. 80

The bridge wall 7 contains two portions 11 and 12 each of which comprises a round bottom groove 13 that extends in an arcuate path 14 through the head of the anchor. The configuration of this groove forms the so-called "thimbleeye" or thimble against which a strain member is adapted to lie without the intervention of a separate protecting thimble. The radius of the arcuate path 14 is sufficient to prevent a strand disposed in the groove from being sharply kinked at any one point. This eliminates concentrated strain on the strand 95 100

and anchor and minimizes the likelihood of damage to the protective coatings on the anchor and strand. The two thimbles 11 and 12 are separated by a projection 15 which prevents a strain member engaged with one of them from coming into contact with a strain member engaged with the other.

The anchor head is provided with a third "thimbleye" or thimble formed in the end piece 9 and comprising a round bottom groove 16 defined by wall members 17 and 18 of the head structure. This groove extends in an arcuate path from the end piece 9, through the perforation 10 and back to the end piece 9, and is of sufficiently long radius to permit a strain member to be engaged with it without the intervention of a protecting thimble. The side wall members 17 and 18 rising out of the groove 16 at one of its ends, and corresponding members 17' and 18', rising out of the groove at the opposite end, serve to retain the strain member in accurate registration with the thimble.

The anchor of my invention is preferably made from round steel rod stock which is first heated and upset by endwise forging to gather metal for the head. The head is then shaped, preferably by a drop forging operation made with suitable dies which are shaped to form the inside surfaces of the head in smooth arcuate contour so that there are no sharp corners or projections which can come into contact with strain members registered with the anchor. The outside surfaces of the anchor are likewise smooth so that the danger of a person being injured by accidentally coming in contact with the anchor is minimized. The anchor thus formed is preferably coated with a suitable protective coating to prevent it from rusting, this coating being applied in any preferred manner, such as, for example, by the usual and well known hot galvanizing process.

As will be seen in Figures 1, 2 and 3, the strain members that are registered with the anchor may be stranded members such as are commonly employed as messenger strands, guy wires, and the like. If desired, solid wires or rods may be equally well attached to my improved anchor.

As will be seen in Figure 1, when a single strain member 20 is registered with the anchor it is threaded through the single perforation 10 in the small portion of the anchor and brought into registration with the thimble 16 formed therein. This thimble bends the member 20 in an arcuate path so that it may be registered with a suitable clamping device 21 by which it is held in place.

Stresses placed upon the anchor by the single strain member 20 in tension are communicated from the end piece 9 of the head through arm extensions 5 and 6 to the arcuate arms 3 and 4 and through these arms to the rod 1. This tension will tend to straighten

the arms 3 and 4 by drawing their free ends together towards the center line or axis of the rod 1, however the bridge wall 7, consisting of thimbles 11 and 12, reinforces the anchor head at the junction of the arm extensions 5 and 6 with the arms 3 and 4 respectively, and the forces tending to bring the free ends of the arcuate arms 3 and 4 together will place this bridge wall 7 under compression. Thus the bridge wall 7 is made to resist the tendency of the stresses placed upon the anchor through the strain member 20 engaged with thimble 16 to deform the head of the anchor. With the strain member 20 properly aligned with respect to the anchor the strains set up in it are equally divided between the arms 3 and 4 of the head and transmitted thereby axially along the anchor rod. The rod is thus placed in tension and there are no forces present tending to bend or distort the same.

In many instances it may be advantageous to register two strain members 22 and 23 with the anchor, in which case these members are threaded through the cardioid opening 8 and brought into registration with the thimbles 11 and 12, respectively. The projection 15 on the bridge wall 7 prevents the members 22 and 23 from coming into contact with each other. When properly aligned so that the axis of the anchor rod 1 bisects the angle between the strain members 22 and 23 these members place a stress upon the anchor which is transmitted equally through arms 3 and 4 to the rod 1. This places the arms 3 and 4 under a tension which tends to straighten them, and under these circumstances the arm extensions 5 and 6 serve to reinforce the head and prevent its deformation. The stresses which tend to straighten the arms 3 and 4 are communicated to those arms through the bridge wall 7, and these same forces will tend to separate the arm extensions 5 and 6. This separation is prevented by the integrally formed end wall 9 which is thus placed in tension to prevent the arm extensions 5 and 6 from separating, and thus to prevent deformation of the anchor head by the strain placed upon it by strain members 22 and 23.

In Figure 3 I have illustrated my improved anchor with three strain members 24, 25 and 26 attached to it. The member 24 is registered with the thimble 16 and places stresses upon the anchor in the same manner as the strain member 20 of Figure 1. Strain members 25 and 26 are registered with thimbles 11 and 12, respectively, and stress the anchor in the same manner as strain members 22 and 23 of Figure 2. It will be noted that the projections 17 and 18 and 17' and 18' separate the strain members 25 and 26 from the thimble 15 and the strain member 24 registered therewith and each of the strain members are therefore independently registered with the anchor and capable of being tensioned to the required degree without interference from the others.

Under these conditions the stresses set up in the anchor head by the tension of strain member 24 upon the thimble 16 are prevented from deforming the head by the reinforcing action 5 of the bridge wall 7 in compression, and the stresses set up in the head by strain members 25 and 26 are prevented from deforming the head by the reinforcing action of the end wall 9 in tension. When the strain members 24, 10 25 and 26 are properly aligned with respect to the axis of the anchor rod 1, the resulting force placed upon the rod by these members is along the axis of the rod and there is no tendency for the rod to bend or twist.

15 In Figure 1 I have shown the anchor with its head 2 disposed in a vertical plane, that is with the openings 8 and 10 running transversely through it along a substantially horizontal axis. In Figures 2 and 3 I have shown 20 the anchor with its head disposed in a horizontal plane and with the openings 8 and 10 therein extending along a substantially vertical axis. These two positions of the anchor are shown by way of example only as the anchor 25 may be turned about its axis into any desired position to meet the requirements of existing conditions. Preferably the anchor is used in the manner shown in Figure 1. In this position the side arm members of the 30 head protect the surface of engagement of the strain members with the thimbles and the tendency of the strain members and thimbles to rust along that line of engagement will be thereby minimized.

35 The rod 20 may be made in a number of different lengths to meet particular requirements. If my improved anchor is used as a guy rod, the rod 1 will be several feet in length and its free end, not shown, may be 40 threaded for the reception of a nut by which it is attached to a dead man. The free end of the rod may be provided with a suitable head for registering it with the now commercially available anchor plates. If the anchor 45 is used as a pole top strain member, the rod 1 will be only of sufficient length to extend through the pole and its free end will be threaded for the reception of a nut by which it is attached to the pole. The diameter of 50 the rod 1 will of course depend upon the desired strength to be built into the anchor. With a rod 1 of a particular diameter and the head 2 proportioned with respect thereto as shown in Figure 4, the head structure it- 55 self will be stronger than the rod and the anchor will therefore have the maximum strength possible with that particular diameter of rod.

While I have chosen to show my invention 60 by illustrating a preferred embodiment of it, I have done so by way of example only as there are many modifications and adaptations which can be made by one skilled in the art within the teachings of the invention.

65 What I consider new and desire to have pro-

tected by Letters Patent is pointed out in the appended claims.

What is claimed is:—

1. A strain bolt comprising a rod and a head containing a plurality of thimbles for receiving a single strand and/or a pair of strands, said thimbles being arranged in two groups, one group comprising a single thimble centered on the axis of the rod and the other group comprising two thimbles located 70 between said single thimble and said rod and equidistant from the axis of said rod, each of said thimbles being formed to afford a round bottom groove extending through the anchor head in an arcuate path of long 75 radius for receiving a strain member.

2. A strain bolt comprising a rod and a head containing a plurality of thimbles for receiving a single strand and/or a pair of strands, said thimbles being arranged in two 80 groups, one group comprising a single thimble centered on the axis of the rod and the other group comprising two thimbles located between said single thimble and said rod and equidistant from the axis of said rod, 85 each of said thimbles being formed to afford a round bottom groove extending through the anchor head in an arcuate path of long radius for receiving a strain member, the walls of said head adjacent said single 90 thimble and between said two thimbles forming guides for preventing a strain member in one of said grooves from coming into contact with the strain members in the other 95 grooves.

3. A strain bolt comprising a rod and an integrally formed head having a wide portion adjacent the rod and a narrow portion at its free end, there being an opening of substantially cardioid shape in the wide portion 105 of said head and a substantially round opening in the narrow portion thereof, the walls of said openings being formed with round bottom grooves extending through the head in arcuate paths of long radius for receiving 110 strain members.

4. An anchor comprising a rod and a per- 115 forate head containing two openings separated by a bridge wall, said wall containing two thimbles for receiving strands passed through one of said openings and said head containing a thimble for receiving a strand passed through the other one of said openings.

5. An anchor comprising a rod and a per- 120 forate head containing two openings separated by a bridge wall, said wall containing two thimbles centered equidistantly from the axis of said rod for receiving strands passed through one of said openings, and said head containing a thimble for receiving a strand passed through the other one of said openings.

6. An anchor comprising a rod and a per- 125 forate head containing two openings sepa-

130

rated by a bridge wall, said wall containing two thimbles for receiving strands passed through one of said openings, and said head containing a thimble centered on the axis of said rod for receiving a strand passed through the other one of said openings.

7. An anchor comprising a rod and a perforate head containing two openings separated by a bridge wall, there being a pair of thimbles on said bridge wall separated by an arcuate projection located substantially on the axis of said rod, said thimbles being adapted to receive a pair of strands projected through one of said openings and said projection being adapted to separate said strands and to keep them in registration with said thimbles, and a third thimble in said head for receiving a strand passed through the other one of said openings.

8. An anchor comprising a rod terminating in a head formed integrally therewith, said head comprising a pair of arcuate arms of oval section extending from the end of the rod and merging into extensions which converge toward the axis of the rod, a thimble joining the ends of said extensions and a pair of thimbles joining the junctions of said arms and extensions.

9. An anchor comprising a rod, a pair of arcuate arms formed integrally with the end of said rod, a pair of thimbles formed integrally with the free ends of said arms and spaced equidistantly from the axis of said rod, extensions of said arms converging beyond said thimbles, and a thimble formed integrally with said arm extensions and centered upon the axis of said rod, said arm extensions and the intervening thimble bracing said arms against deformation by strains placed upon said pair of thimbles.

10. An anchor in which a pair of adjacently disposed thimbles are connected to a rod by a pair of integrally formed arcuate arms extending from the outside ends of the thimbles, a brace for enabling said arms to resist bending under strains placed on said thimbles comprising integral extensions of said arms converging from the ends of said thimbles and joined together on the side of said thimbles away from said rod.

11. An anchor comprising a rod, a pair of arms formed integrally with the rod and diverging in arcuate paths from the end thereof, extensions on said arms converging toward a point on the axis of said rod beyond said arms, a thimble joining the free ends of said arm extensions, a pair of thimbles formed as a bridge wall connecting said arms at the junctions of said extensions therewith, said first thimble and arm extensions bracing said arms against deformation under stresses placed on said anchor by strands encircling said pair of thimbles, and said pair of thimbles bracing said arms and extensions against deformation under stresses placed on said

anchor by a strand encircling said first thimble.

In witness whereof, I hereunto subscribe my name this 17 day of Nov., 1931.

WILBUR R. POUNDER.
